SCRUBBER STRUCTURE

Filed Dec. 14, 1936

UNITED STATES PATENT OFFICE

2,123,308

SCRUBBER STRUCTURE

Anders R. Lofstrand, Sr., Washington, D. C.

Application December 14, 1936, Serial No. 115,869

3 Claims. (Cl. 15—176)

This invention relates to a scrubber structure of the brush type designed primarily for use in connection with machines for washing, rinsing and drying drinking glasses as disclosed by Letters Patent 1,992,920 and 2,052,835, but it is to be understood that a scrubber structure, in accordance with this invention, is to be employed in any connection for which it may be found applicable, and the invention has for its object to provide, in a manner as hereinafter set forth, a structure of the class referred to including a vertically movable spring controlled scrubbing element for encompassing and acting on the closed end or bottom and outer periphery of the body of a drinking glass bordering such closed end while the glass is subjected to a washing operation.

A further object of the invention is to provide, in a manner as hereinafter set forth, a scrubber structure including an extendible detachable scrubbing element of brush-like form.

A further object of the invention is to provide, in a manner as hereinafter set forth, a scrubber structure including a vertically movable cushioned carrier and an expandable scrubbing element capable of being detachably connected to the carrier whereby when worn or impaired, it may be readily detached and a non-worn or non-impaired element substituted without discarding the carrier.

A further object of the invention is to provide, in a manner as hereinafter set forth, a scrubber structure including a scrubbing element formed of a circular outer portion for scrubbing that part of the outer periphery of the glass bordering the closed end of the latter and an inner portion arranged within and disposed diametrically of the circular portion for scrubbing throughout the outer face of the closed end of the glass.

A further object of the invention is to provide, in a manner as hereinafter set forth, a scrubber structure including a skeleton scrubbing element and a vertically movable cushioned carrier therefor having means for detachably coupling said element thereto to bodily move therewith, as well as extending such element during the coupling of the latter with the carrier.

Further objects of the invention are to provide, in a manner as hereinafter set forth, a scrubber structure which is simple in its construction and arrangement, strong, durable, compact, readily assembled, thoroughly efficient in its use and comparatively inexpensive to manufacture.

To the above ends essentially and to others which may hereinafter appear the invention consists of the novel construction, combination and

arrangement of parts as will be more specifically described and are as illustrated in the accompanying drawing wherein is shown an embodiment of the invention, but it is to be understood that changes, variations and modifications may be resorted to which fall within the scope of the invention as claimed.

In the drawing:—

Figure 1 is an elevation of the scrubber structure shiftably suspended from a support, the latter being shown in section.

Figure 2 is an inverted plan of the structure, Figure 3 is a top plan view,

Figure 4 is a section on line 4—4, Figure 3, and Figure 5 is a section on line 5—5, Figure 3.

As is well known and as disclosed by the patentees aforesaid, when scrubber structures are employed in machines for washing drinking glasses, the structures are employed in a group, the number of structures of the group depending upon the number of glasses which are to be subjected simultaneously to the washing operation. The structures of the group are arranged in spaced relation. The group is carried by a support common thereto. The structures are slidably mounted in the support. When the glasses are subjected to the washing operation they are inverted and mounted in a tray or basket. The latter with the glasses therein is lowered into and supported in lowered position within a washing compartment. The support carrying the group of scrubber structures is then lowered into the compartment aforesaid until the scrubbing structures yieldably engage the closed ends of the glasses. During the washing operation the glasses are resiliently held against the scrubbing structures and this action is continued until the finish of the washing operation, after which the scrubbing structures and then the tray or basket with the washed glasses are removed from the washing compartment.

With reference to the drawing the support which slidably suspends a group of scrubber structures is fragmentarily shown and is illustrated in connection with a single scrubber structure. The support, indicated at 1 is formed with a vertical opening 2 surrounded at its upper end by a vertically disposed annular boss 3 of frusto-conoidal contour. The number of openings 2 and bosses 3 will correspond to the number of scrubber structures which are to be suspended from support 1. The openings 2 will be arranged in spaced relation. Forms of supports for suspending a group of scrubber structures are set forth in the patents aforesaid. No claim is made to the support in this application as the support is shown for the

purpose of showing the adaptation of a scrubber structure in slidably suspended relation with respect to a support.

A scrubber structure, in accordance with this invention, includes a vertically movable cushioned carrier 4 adapted to be slidably suspended from the support 1 and a scrubbing element 5 which is detachably connected to the inner or lower end of carrier 4.

10 The carrier 4 includes a shaft 6, a coupler 7, a cushioning spring 8, a hanger 9 and a retaining screw 10. The shaft 6 is formed lengthwise of the axis thereof with a screw threaded socket 11 opening at the outer end 12 thereof. The socket 11 is of less length than that of shaft 6. The latter is of circular cross section and includes portions 13, 14 of different diameters. The portion 13 is of greater length and of greater diameter than the portion 14. The junction of the 20 portions of different diameters provides a shoulder 15. The portion 14 merges into the inner end of portion 13. The latter is formed with a key-way 16 which extends from shoulder 15 to shaft end 12. The coupler 7 includes a plate formed 25 of an intermediate part 17 and a pair of oppositely extending end parts 18, 19. The part 17 is of greater width than the parts 18, 19 and is formed with a vertical opening 20 at its axis. The lower face of part 17 is formed with an annular rabbet 21 which borders the lower end of opening 20. The outer end edges 22, 23 of the 30 parts 18, 19 respectively are of arcuate contour and oppositely disposed. The lower faces of the parts 18, 19, inwardly adjacent to the edges 22, 35 23 have depending oppositely disposed frictional clamping ribs 24, 25 respectively of segmental contour. The portions 26, 27 of the lower faces of the parts 18, 19, outwardly adjacent the ribs 24, 25 respectively, are to be arranged in superposed relation with respect to the top of the circular portion, to be referred to, of the scrubbing element 5. The portion 14 of shaft 6 extends into opening 20, the shoulder 15 bears against the upper face of coupler 7, the inner end of shaft 45 portion 14 is upset, as at 28 and arranged in the rabbet 21 whereby the inner end 28 of shaft portion 14 will coact with the shoulder 15 to connect shaft 6 to coupler 7. To prevent the carrier 4 from bodily revolving relative to support 1 the 50 boss 3 is provided with a stop, in the form of a pin, screw or lug and shown by way of example a pin 29 which extends into the key-way 16. The size of the pin 29 relative to the width of the key-way 16 is such as not to prevent the 55 vertical movement of the carrier 4 relative to support 1.

The scrubbing element 5 is of skeleton form and includes a circular split extendible hollow head 30 opening throughout its lower face, as at 31 and provided with a pair of spaced depending outwardly inclined parallel flanges 32, 33 integral with the split ends of the head. Extending into and throughout and depending from the head 30, as well as being clamped thereto by the flanges 32, 33 is a scrubbing member 34 corresponding in length to that of head 30 and consisting of rows of bristles arranged in a manner to provide

that portion of member 34 which depends from flanges 32, 33 of tapered form. The flanges correspond in length to that of the head 30. The latter is formed of a split annular outer portion 35 and an inner portion 36 which is disposed within and diametrically with respect to the portion 35. The flanges 32, 33 direct the rows of bristles at an outward inclination with respect to the portion 35 of head 30 and also at an inclination with respect to the portion 36 of head 30. The bristles of the rows of bristles carried by portion 36 of head 30 are of less height than the bristles carried by portion 35 of head 30.

The distance between the outer side edges of the ribs 24, 25 is slightly greater than the inner diameter of portion 35 of head 30. The ribs are adapted to bear against spaced parts of the inner side of the said portion 34, whereby the latter will be extended and detachably frictionally clamped to coupler 7.

Surrounding the shaft 6 is a coiled cushioning spring 37 which seats at its inner end on coupler 7. When the structure is moved upwardly, the outer end of spring 37 abuts support 1 and cushions such upward movement.

The hanger 9 of the carrier 4 is in the form of an annulus 38 mounted on and of greater diameter than that of the outer end of shaft 6. The hanger 9 is secured on shaft 6 by the headed retaining screw 10 extending through the hanger 9 and engaging the wall of socket 11.

When the scrubber structure is in its lowermost position, the hanger 9 seats on the upper edge of boss 3 (Figure 1).

What I claim is:—

1. In a scrubber structure, a brush structure formed of an annular portion carrying a brush element, and a rigid plate having means on its upper face for connecting it with a shaft and a pair of ribs on its lower face in the form of segments of a circle diametrically oppositely located for frictionally engaging the inner face of opposite sides of said annular portion.

2. In a scrubber structure, a brush structure including a brush element carrying part formed of an annular portion and a portion extending inwardly from the annular portion, and a rigid plate overlapping the annular portion and having end edges lying within the perimeter of the brush structure, said plate having means on its upper face for connecting it with a shaft and a pair of ribs on its lower face in the form of segments of a circle diametrically oppositely located for frictionally engaging the inner face of opposite sides of said annular portion.

3. In a scrubber structure, a brush structure formed of an annular portion carrying a brush element, and a rigid plate overlapping the annular portion and having end edges lying within the perimeter of the brush structure, said plate having means on its upper face for connecting it with a shaft and a pair of ribs on its lower face in the form of segments of a circle diametrically oppositely located for frictionally engaging the inner face of opposite sides of said annular portion.

ANDERS R. LOFSTRAND, SR.
